The ornamental design for a tennis racquet frame, as
shown and described.

DESCRIPTION

FIG. 1 is a front elevational view of a tennis racquet
frame showing my new design.

FIG. 2 is a top plan view thereof,

FIG. 3 is an end elevational view thereof; and

FIG. 4 is a cross sectional view taken along 4—4 in
FIG. 1.

The side opposite to that shown in FIG. 1 is the mirror
image thereof.
